UNITED STATES PATENT OFFICE.

GEORGE E. SHIRLEY, OF ALBA, MISSOURI.

DESIGN FOR A FLUE-CLEANING BLADE.

59,382.

Specification for Design.

Patented Oct. 11, 1921.

Application filed May 24, 1920. Serial No. 383,993. Term of patent 7 years.

To all whom it may concern:

Be it known that I, GEORGE E. SHIRLEY, a citizen of the United States, residing at Alba, in the county of Jasper and State of Missouri, have invented a new, original, and ornamental Design for a Flue-Cleaning Blade, of which the following is a specification.

The accompanying drawing is a perspective view and illustrates my ornamental design.

It is characterized by a bar having an

oblique offset which is fashioned with a twist to bring the bar into a plane at right angles to its upper portion. Quadrant plates with curved edges project from the shank bar and triangular webs lead from the quadrant plates to the shank bar. The latter terminates in a rounded end. The whole is of pleasing design.

What I claim is—

The ornamental design for a flue cleaning blade, as shown and described.

GEORGE E. SHIRLEY.
